UNITED STATES PATENT OFFICE.

MATILDA COOK, OF CHICAGO, ILLINOIS, ASSIGNOR TO GAGE BROTHERS & CO., OF CHICAGO, ILLINOIS, A CORPORATION OF ILLINOIS.

DESIGN FOR A HAT.

49,509.

Specification for Design. Patented Aug. 15, 1916.

Application filed May 18, 1916. Serial No. 98,465. Term of patent 3½ years.

To all whom it may concern:

Be it known that I, MATILDA Cook, a citizen of the United States, residing at Chicago, in the county of Cook and State of Illinois, have invented a new, original, and ornamental Design for Hats, of which the following is a specification, reference being had to the accompanying drawing, forming part thereof.

I claim:—

The ornamental design for a hat as shown.

MATILDA COOK.
